UNITED STATES PATENT OFFICE.

PAUL J. MARKS, OF ROCHESTER, NEW YORK, ASSIGNOR TO EASTMAN KODAK COMPANY,
OF ROCHESTER, NEW YORK, A CORPORATION OF NEW YORK.

PHOTOGRAPHIC SHUTTER.

1,243,086.

Specification of Letters Patent.

Patented Oct. 16, 1917.

Application filed November 23, 1915. Serial No. 62,946.

To all whom it may concern:

Be it known that I, PAUL J. MARKS, of Rochester, in the county of Monroe and State of New York, have invented certain new and useful Improvements in Photographic Shutters; and I do hereby declare the following to be a full, clear, and exact description of the same, reference being had to the accompanying drawings, forming a part of this specification, and to the reference-numerals marked thereon.

My present invention relates to photography and more particularly to photographic shutters and it has for its object to provide an improved pivoted blade shutter that may be wound up in one operation to furnish the power for a number of successive operations or exposures whereby the shutter will have the advantages of the automatic type of shutter and also the speed strength of a set shutter. Another object of the invention is to provide a simple and efficient retarding mechanism for regulating the duration of automatically timed exposures. The improvements are further directed toward the winding mechanism, the operating means or controller and the adjusting means for setting the timing devices. To these and other ends the invention resides in certain improvements and combinations of parts all as will be hereinafter more fully described, the novel features being pointed out in the claims at the end of the specification.

In the drawings:

Figure 1 is a front elevation of a shutter constructed in accordance with and illustrating one embodiment of my invention;

Fig. 2 is a similar view of the bottom of the shutter case with the actuating and controlling mechanism removed to reveal the blade mechanism;

Fig. 3 is a detail plan view of one of the cover plates with an upper cover plate removed to reveal the registering dial of the winding mechanism;

Fig. 4 is a front view of the shutter with all of the cover plates removed;

Fig. 5 is a similar view with the timing mechanism and certain other parts removed;

Fig. 6 is a detail section taken substantially on the line 6—6 of Fig. 4;

Fig. 7 is another detail section taken substantially on the line 7—7 of Fig. 5;

Fig. 8 and Fig. 9 are front views partly in section through the actuating device and with still more of the mechanism removed,

these views being principally illustrative of the actuating and retarding devices;

Fig. 10 is a detail bottom view of the winding arbor shown in Fig. 6;

Fig. 11 is a view similar to Figs. 8 and 9 showing the retarding mechanism in another position;

Figs. 12, 13, 14 and 15 are fragmentary front views showing the controlling mechanism in different positions during time, bulb and instantaneous or automatically timed exposures;

Fig. 16 is a detail view showing the impact member of the actuating mechanism in a certain position with reference to the operating member and the retarding mechanism, and

Fig. 17 is a detail sectional view taken substantially on the line 17—17 of Fig. 5 but with the casing cover plate in place.

Similar reference numerals throughout the several figures indicate the same parts.

Referring first to Figs. 1, 2 and 3, 1 indicates the shutter casing, 2 the central lens tube connection and 3 Fig. 2 the annular chamber surrounding the latter in which most of the mechanism to be described is housed. The chamber 3 is closed by an annular cover plate 4 and a separate extension 5 on this, secured by screws 6, covers an extension 7 of the casing that accommodates part of the winding and actuating mechanism.

Any suitable blade mechanism may be employed, one comprising five blades indicated at 8 being utilized in the present instance. This blade mechanism is confined, as usual, between the bottom of the casing 1 and a partition 9 that separates the blade mechanism from the actuating and control mechanism. These blades have pivots 10 journaled in the bottom of the casing and the partition 9 to turn on fixed axes and are also pivotally engaged each by a pin 11 on a rotary shutter ring 12. Reciprocation of the ring first in one direction and then the other both opens and closes the shutter blades and the pins 11 work in slots 13 in the partition 9. At least one of the pins projects forwardly of the partition to be acted upon by the shutter actuating mechanism in a manner hereinafter described.

Before leaving Figs. 1 and 2, it may be explained generally with reference thereto that 14 is the shutter winding key, 15 is the disk that is rotated to adjust the mechanism

for time, bulb and the instantaneous and automatically timed exposures and 16 is the disk for adjusting the aperture of the usual iris diaphragm shown at 17 in Fig. 5. Rotation of the disk 16 turns a gear 17^a Fig. 4 meshing with a toothed ring 18 connected to the diaphragm blades but as this forms no part of the present invention, detailed description is not necessary.

10 Referring now more particularly to Figs. 4, 5, 6, the winding key 14 is fixed to an arbor 19 journaled in the cover plate 5 at 20 and in the partition plate 9 at 21. A clock spring 22 has its inner end fixed to the 15 arbor and its outer end anchored to the casing at 23. Below the spring is a large gear 24 having a recess on its under side closed by a disk 25 which forms the bearing for the gear on the arbor 19 with relation 20 to which latter the gear is free to turn. The gear is provided with radial slots 26 forming stops for the engaging end 27 (Fig. 10) of a segmental spring pawl 28 occupying the recess in the gear and secured 25 to the arbor by screws 29. The gear 24 is prevented from rotating to the right or clockwise by a pawl 30 Fig. 5 and thus the spring may be wound by turning the key 14 to the right and the gear placed under 30 tension tending to turn it to the left through the medium of the pawl 28 locked in the stops 26. It is normally prevented from turning to the left, however, by the shutter operating lever 31 through the medium of 35 the following mechanism:

An intermediate gear 32 transmits motion from the gear 24 to a gear 33 on an arbor 34. Fixed to this gear 33 and lying beneath it is a member having four contact teeth 35-35 and 36-36, the last mentioned two teeth being offset in a plane above the first mentioned two Fig. 17. The shutter operating member 31 has an enlarged portion 37 Fig. 5 pivoted at 38 and provided with 40 two stop shoulders 39 Fig. 16 and 40. The stop shoulder 39 is in the plane of the contact teeth 36 and is normally held in their path by a spring 41, Fig. 8 while the stop shoulder 40 is offset into the plane of the 45 contact teeth 35 though it is normally held out of their path by the same spring 41. The normal position of the shutter is shown in Fig. 5 and at this time one of the contact teeth 36 is always in engagement with 50 the stop shoulder 39 which locks the gear 33 and also, through gear 32, the large gear 24 and prevents the latter from being turned by the spring.

When the operating lever 31 is depressed, 60 the stop shoulder 39 is withdrawn from the contact tooth 36 and the stop shoulder 40 is thrust into the path of the succeeding contact tooth 35 which it engages to halt the gear train as shown in Fig. 16, after 65 about a half revolution of the small gear

and the member carrying the contact teeth. Upon the return of the operating member 31 to its normal position under the influence of its spring 41, the engagement at 35-40 is broken again but the subsequent movement of the train as the next contact tooth 36 moves into engagement with the other stop shoulder 39 is an idle one and is so slight that it permits the large gear 24 to 70 rotate hardly at all.

The blade mechanism is actuated by the spring under the control of the gearing in the following manner:

Formed on the disk 25 or otherwise fixed with relation to the large gear 24 is a star wheel 42 (Figs. 6, 8 and 9) that revolves to the left as the gear train is driven by the spring and that co-operates with a vibrating escapement member 43 Fig. 8 surrounding 80 it. This escapement member is pivoted to the extension of the partition member 9 at 44 on one side of the star wheel and has a notch 45 Fig. 9 on the opposite side of the star wheel that engages one of the pins 11 of the blade ring 12, the adjacent portion of 85 the member being offset into the plane of the pin, as shown, to occupy a recess 46 Figs. 6 and 9 in the partition 9. Contact with the star wheel is made by two inwardly projecting cam teeth 47 and 48 on the member 90 43. The normal position of the star wheel and escapement relatively to each other is shown in dotted lines in Fig. 5 with the tooth 47 in endwise engagement with one of the teeth of the star wheel. The escapement member being in its extreme position 95 to the right, the shutter blades are closed and the beforementioned endwise engagement of the teeth locks them closed so that 100 they can not be jarred open or opened at all except through the movement of the actuating mechanism. When the gear train is released, the two teeth referred to pass out of engagement as shown in Fig. 8, and concurrently therewith another tooth on the star 105 wheel rides against the escapement tooth 48 which latter climbs into endwise engagement with the star wheel tooth as shown in 110 the same figure. The member 43 is thus 115 swung to the left opening the shutter blades and while they are open, the endwise engagement of the tooth 48 is continued so that the blades are locked in their open position in the same manner that they are locked in 120 their closed position.

On the whole, therefore, it will be understood that during one actuation of the shutter, that is, the opening and closing of the blades, the escapement member 43 makes one complete vibration from the position of Fig. 5 to that of Figs. 8 and 9 and back again.

The retarding mechanism controlling the interval during which the shutter is held open in the position of Fig. 8 is connected 130

to the actuating mechanism through the medium of a segment arm 49 Figs. 5 and 8 pivoted at 50 and normally held by a spring 51 (Fig. 4) in a position in which a finger 52 thereon lies in the path of two contact arms 53 (Fig. 5) carried by a disk 54 fixed to the small gear 33 of the train. The two arms 53 lie in the same plane and the impact of one and then of the other transmits the power of the actuating mechanism to the retarding mechanism upon successive operations of the shutter. When the shutter actuating mechanism is released from the position of Fig. 5, a contact arm 53 Fig. 8 revolves in advance of the stop tooth 35 that is to next engage the stop shoulder 40 and picks up the finger 52, as shown in Fig. 8. It finally slips off of the said finger when such stop engagement takes place, as shown in Fig. 16, and allows the finger and arm 49 to return to initial position under the influence of spring 51.

A segment 54 Fig. 8 on the arm 49 is in constant mesh with a small gear 55 fixed to the shaft of an escapement wheel 56 journaled in the partition 9 and in a spaced journal plate 57. Coöoperating with this escapement wheel is an anchor 58 pivoted at 59 so that as the sweep of the segment arm 49 rotates the escapement wheel, the anchor 58 thereon vibrates rapidly. To impede its vibration, however, a segment 60 thereon may mesh with a small gear 61 on the shaft of a fly wheel 62 journaled in a rocking yoke 63 pivoted at 64. There is thus opposed to the force of the actuating mechanism the inertia of the fly wheel 62 with its operating segment, the resistance of the escapement 56 and the inertia of the arm 49 which latter constitutes, by reason of the gearing 55 and the contact at 52, an intermediate mechanism or member interposed between the actuating mechanism and the main retarding elements and all of these act in the capacity of retarding means.

To vary the effect of the retarding action in the different automatically timed exposures, the throw of the segment arm 49 is regulated. To this end, an arbor 65 turned by the adjusting disk 15 on the exterior of the shutter casing carries fixed thereto a cam 66 Fig. 5 coöoperating with a pin 67 Fig. 9 on an extension 68 of the segment lever 49. When the lever is to have its full throw from the starting position of Fig. 5, the cam is in the position there shown, but when it is desired to shorten the throw, the cam is turned to the position of Fig. 11, for instance, which, in this particular structure, shows the adjustment for 1/25th of a second. The segment lever is thereby prevented from returning fully under the influence of spring 51 and therefore receives the impact of the contact arm 53 at a later point though it leaves contact therewith

always at the same point. In other words, the contact arms of the actuating mechanism pick up the retarding device later and do not remain under its impeding influence so long when the lever 49 is set for a short throw 70 and a rapid exposure.

In order to permit the segment arm 49 to return quickly under the influence of its spring 51 to its initial position after one operation of the shutter, an arrangement is provided which automatically throws out part of the retarding mechanism after the said mechanism has performed its retarding function. The gear 61 on the shaft of the fly wheel 62 is normally held in mesh with the segment 60 of the escapement anchor by a spring 69 Fig. 9. An arm 70, however, proceeding from the journal yoke 63 extends around to the neighborhood of the impact devices on the arbor 34 and occupies the same plane with the fingers or contact teeth 36 which coöperate with the stop shoulder 39 of the shutter operating member. Just after one of the contact arms 53 leaves the finger 52 during an operation of the shutter, the tooth 36 that has been released from the stop shoulder 39 comes in contact with this arm 70 before the other contact tooth 35 has reached stop shoulder 40 and depresses said arm 70. This rocks the journal yoke 63 against the tension of its spring 69 and carries the gear 61 out of mesh with segment 60 permitting the segment arm 49 to return the escapement without the drag of the fly wheel 62 being upon it. In fact, the fly wheel is normally held out of gear, as shown in Fig. 5, as, after coming in contact with the arm 70, the tooth 36 is halted and it does not progress far enough to leave this contact while the locking of the actuating mechanism is being transferred from one of the contact teeth 35 at 40 to the other contact tooth of the pair that actuates the arm 70.

This throwing out of the fly wheel is not only of value in returning the parts, but is utilized for the very rapid exposures so that even though the throw of the main segment 54 is reduced to a minimum, it will also itself find minimum resistance in the escapement. For this purpose, another cam 71 Fig. 5 is fixed to the arbor 65 to engage a projection 72 on the arm 70 and permanently maintain it depressed in the same manner as do the teeth 36. Both of the cams 66 and 71 being on the same arbor 65, but the one adjustment is required to throw out the fly wheel and give the minimum swing to the lever 49.

The arbor 65 is preferably provided with a ratchet device 73 Fig. 5 to prevent it from being turned in the wrong direction.

For the ordinary time exposures, not of predetermined duration, and for bulb exposures time and bulb stops are provided under the control of an extension 74 Fig. 13e

9 of the main operating lever 31. Referring more particularly to Figs. 12 to 14, the time stop 75 is pivoted at 76 and its pivot is encircled by a spring, one arm 77
5 of which tends to rock the time stop to a position in the path of an abutment 78 on the retarding lever 49. The other arm 79 of the spring similarly tends to move the bulb stop 80 pivoted at the same point, into the
10 path of the abutment 78. An arm 81 on the time stop extends in front of the extension 74 of the shutter operating member while an arm 82 on the bulb stop extends in rear of such extension. A cam 83 Fig. 13 fixed
15 uppermost on the arbor 65 has a recess 84 therein and the time stop 75 may enter the path of the abutment 78 on the retarding lever only when the cam 83 is turned to a position in which a projection 85 Fig. 14 on
20 the arm 81 may enter this recess. Similarly, a cam 86 on the arbor 65 beneath cam 83 (Fig. 7) has a recess 87 Fig. 13 that takes a projection 88 on the bulb stop 80 to permit the bulb stop to enter the path of the abutment 78.
25

When the arbor 65 is turned so that both time and bulb stops have freedom of movement, as shown in Figs. 12 and 14, the shutter is adjusted for a time exposure. Upon 30 the first depression of the shutter operating lever 31, the abutment 78 of the retarding lever 49 catches on the bulb stop 80, as shown in Fig. 12, the time stop being moved out of the way by the extension 74 engaging 35 the arm 81. As the operating lever returns to normal position, it releases the bulb stop by engagement with the arm 82 and the abutment 78 is transferred to the time stop 75 which follows under the influence of its 40 spring 77, the shutter blades being held open. Upon the next actuation of the operating lever, the abutment 78 is released from the time stop (Fig. 14) by deflection of the arm 81 and falls between the two 45 stops allowing the segment lever 49 to complete its throw and the shutter blades to close.

A slight turn of the arbor 65 rides the projection 85 of the time stop on to the cam 83 and out of the recess 84 and the time stop is kept out of position altogether for a bulb exposure, as shown in Fig. 13. Thus, when the abutment 78 rides off of the bulb stop 80 on the return of the operating lever 31, it is not caught again and allows the shutter blades to close. The recess 87 in the cam 86 of the bulb stop is sufficiently long to allow it to accommodate the projection 88 after the projection 85 of the cam stop can no longer enter the recess 84 in its cam.

It will be observed that the time stops do not get the full force of an impact from the strong winding spring 22 of the actuating mechanism because they control the latter through the retarding mechanism and they

engage with the long arm of lever 49 while the impact of the contact arm 53 is taken on the short arm 52 with a resultant mechanical advantage to the time stops. Also, the lever 49 thus constitutes a single common connecting member through the medium of which both time stops and the retarding mechanism exert their influence on the actuating mechanism. 70

The present shutter was designed to accomplish twelve exposures with a single winding of the main actuating spring 22. The progress of the exposures is preferably indicated on a dial 89 (Fig. 3) journaled on the cover plate 5 beneath a further cover plate 90 superposed upon the latter and having an opening 91 therein. The dial is provided with the numbers of the successive exposures viewable through the opening 91 and is fixed to a gear 92 driven by a gear 93 on the winding arbor 19. As the spring is wound up a stop 93^a on the gear 92 limits the winding movement by engaging a fixed abutment 94 on the cover plate 5 and when the spring is run down, the stop halts against a similar abutment 95. 75 80 85 90

The shutter is used in the following manner:

The spring 22 is wound up by means of the winding key 14 which stores enough energy, in the present instance, to carry the shutter through twelve operations. The actuating parts are then in the normal position of Fig. 5. If the very shortest or instantaneous exposure is desired, the dial 15 is set with "200" uppermost in Fig. 1. This adjusts the various cams on the arbor 65 of the dial so that the retarding element 62 is thrown out of gear by means of its arm 70; the contact 52 of the segment arm 49 is held so far over that it will hardly be picked up at all by the actuator contacts 53 and hence the arm given such a slight throw as not to operate the escapement 56 to an appreciable extent, if at all, and both the time stop 75 and the bulb stop 80 are held inoperative or in such positions as to permit the passage of the abutment 78 on the segment lever 49 between them were it caused to move. For lengthening the exposure, the dial 15 may be progressively moved to register the other higher fractions, in which case the cam on the arbor 65 allows the finger 52 of the arm 49 to move a progressively greater distance into the path of the actuating contacts 53 which thereby give it a greater throw and cause a more prolonged drag from the gearing with the retarding devices, the time and bulb stops being still inoperative. If time or bulb exposures are required the dial 15 is moved to register "T" or "B" in which case, the appropriate cams on the dial arbor 65 allow one or both of the stops 75 and 80 to come into play in the path of the abutment 78 on the segment lever and 130

halt the cycle of movement of the actuating mechanism so that it is divided into two movements of the shutter blades, during one of which they are opened, and during the 5 other of which they are closed. At this time, the retarding element 62 is held out by its cam and the slowing up of the opening and closing movements because the segment lever 49 that acts on the rest of the retarding mechanism is also the part that coöperates with the time stops, is not sufficient to be of disadvantage. The dial 15 turns only in the one direction and may be reset at any time to cause a proper readjustment of the 10 parts to truly carry out its reading.

I claim as my invention:

1. In a photographic shutter, the combination with a blade mechanism, of actuating mechanism therefor comprising a gear having stops thereon, a spring for driving the gear, an arbor for winding the spring about which the gear freely turns, and a spring pawl carried by the arbor and coöperating with the stops on the gear.
2. In a photographic shutter, the combination with a blade mechanism, of actuating mechanism therefor comprising a gear having a recess in one face, and stops in a wall of the recess, a spring for driving the gear, 20 an arbor for winding the spring and about which the gear freely turns, an annular spring pawl secured to the arbor and occupying the recess in the gear to coöperate with the stops on the latter and a disk secured to and forming the bearing of the gear on the arbor and closing the recess in the latter.
3. In a photographic shutter, the combination with a blade mechanism, of actuating mechanism therefor comprising an arbor, a winding spring connected thereto, a star wheel on the arbor and a vibratory escapement member coöperatively connected to the blade mechanism and having two 40 points of contact with the star wheel to open and close the blades with successive impacts from the star wheel while traveling in one direction.
4. In a photographic shutter, the combination with a blade mechanism, of actuating mechanism therefor comprising an arbor, a winding spring connected thereto, a star wheel on the arbor and a vibratory escapement member pivoted on one side of the 50 arbor to embrace the star wheel and having two inwardly projecting points of contact with the latter to open and close the blades with successive impacts from the star wheel while traveling in one direction, and an operating connection between the escapement member and the blades on the opposite side of the arbor from that of its pivot.
5. In a photographic shutter, the combination with a blade mechanism, of actuating mechanism therefor comprising a vibratory 60

member operatively connected with the blades, a winding spring and a driving member operated by the winding spring and engaging the vibratory member to open and to close the blades and to positively lock the 70 blades at the conclusion of each movement.

6. In a photographic shutter, the combination with blade mechanism, of actuating mechanism therefor comprising a star wheel, a winding spring therefor, and a vibratory 75 member operatively connected with the blades and having two contact teeth to take successive lateral impacts from the star wheel while the latter is traveling in one direction and open and close the shutter, and 80 a shutter operating member operatively connected to the star wheel to halt the latter in endwise engagement with one such contact tooth to positively lock the blades at the conclusion of their movement.

85 7. In a photographic shutter, the combination with blade mechanism, a retarding device and a shutter operating member, of blade actuating mechanism embodying a rotary element having two sets of contacts arranged in different planes coöperating, respectively, with the retarding device and shutter operating member.

8. In a photographic shutter, the combination with blade mechanism, a retarding 90 device and a shutter operating member, of blade actuating mechanism comprising gearing and two sets of contacts arranged in different planes to coöperate, respectively, with the retarding device and shutter operating member and mounted upon the same arbor and in fixed relationship with one of the gears of the blade actuating mechanism.

105 9. In a photographic shutter, the combination with blade mechanism, and actuating mechanism therefor, of retarding means, a member connecting the actuating mechanism with the retarding means and a time stop coöperating with said connecting member.

110 10. In a photographic shutter, the combination with blade mechanism, and actuating mechanism therefor, of retarding means, a time stop and a bulb stop and a common connecting member through the medium of which all three are adapted to act upon the actuating mechanism.

11. In a photographic shutter, the combination with blade mechanism and actuating mechanism therefor, of retarding means, an 120 adjustable member connecting the actuating mechanism with the retarding means, a time stop and a bulb stop for the actuating mechanism and three relatively fixed and jointly operable controlling members coöperating, respectively, with the connecting member, the time stop and the bulb stop.

12. In a photographic shutter, the combination with blade mechanism and actuating mechanism therefor, of retarding means, an 130

adjustable member connecting the actuating mechanism with the retarding means, a time stop and a bulb stop for the actuating mechanism, and an arbor provided with an adjusting member and three cams thereon co-operating, respectively, with the connecting member, the time stop and the bulb stop in different planes.

13. In a photographic shutter, the combination with blade mechanism and actuating mechanism therefor, of retarding means embodying gearing, a segment arm meshing with the gearing and operated by the actuating mechanism and a time stop co-operating with said arm.

14. In a photographic shutter, the combination with blade mechanism, and actuating mechanism therefor, of a retarding means embodying an intermediate mechanism driven by the actuating mechanism having a returning spring and a shiftable element adapted to be thrown in and out of gear with the intermediate mechanism, a controlling member for the shiftable element and means for operating the intermediate mechanism and the said controlling member successively in the order named during the shutter operating movement of the actuating mechanism to throw out the shiftable element after the retarding means has performed its function and permit the quick return of the intermediate mechanism under the influence of its spring.

15. In a photographic shutter, the combination with blade mechanism and actuating mechanism therefor, of a retarding means comprising an arm connecting it with the actuating mechanism, a spring for returning said arm and a shiftable element adapted to be thrown in and out of gear with the arm, a controlling member for the shiftable element, and a rotary contact member driven by the actuating mechanism having a slip-off contact with the connecting arm and arranged to successively engage first it and then the controlling member during the shutter operating movement of the actuating mechanism to throw out the shiftable element and permit the quick return of the rest of the retarding mechanism.

16. In a photographic shutter, the combination with blade mechanism and actuating mechanism therefor, of a retarding means embodying an intermediate mechanism having a returning spring and a shiftable element adapted to be thrown in and out of gear with the intermediate mechanism, a controlling member for the shiftable ele-

ment, means for operating the intermediate mechanism and the said controlling member successively in the order named during the shutter operating movement of the actuating mechanism to momentarily throw out the shiftable element after the retarding device has performed its function and permit the quick return of the intermediate mechanism and separate means for locking out the shiftable element during the operative movement of the retarding mechanism.

17. In a photographic shutter, the combination with blade mechanism and actuating mechanism therefor, of retarding means connected with the latter embodying a shiftable element, a controlling means for the shiftable element to throw it out of gear, and a common adjusting member for limiting the throw of the retarding means and for operating the controlling element.

18. In a photographic shutter, the combination with blade mechanism and actuating mechanism therefor, of retarding means connected with the latter embodying a shiftable element, a controlling means for the shiftable element to throw it out of gear, time and bulb stops, means connecting the latter with the actuating mechanism to control the same, and a common adjusting member for limiting the throw of the retarding means, for operating the controlling element and for regulating the time and bulb stops.

19. In a photographic shutter, the combination with blade mechanism and actuating mechanism therefor, of a retarding mechanism comprising an escapement wheel, an anchor co-operating therewith, a segment on the anchor, a fly wheel geared with the segment and a segment arm geared to the escapement wheel and operated by the actuating mechanism.

20. In a photographic shutter, the combination with blade mechanism and actuating mechanism therefor, of a retarding mechanism comprising an escapement wheel, an anchor co-operating therewith, a segment on the anchor, a fly wheel having a gear movable into and out of mesh with said segment, a segment arm geared to the escapement wheel and connected with the actuating mechanism, and means for shifting the fly wheel gear.
